(57) **CLAIM**

The ornamental design for a table tennis paddle, as shown and described herein.

DESCRIPTION

FIG. 1 is a perspective view of a design of a table tennis paddle.

FIG. 2 is a first elevation view of the table tennis paddle of FIG. 1.

FIG. 3 is a second elevation view of the table tennis paddle of FIG. 1.

FIG. 4 is a first side elevation view of the table tennis paddle of FIG. 1.

FIG. 5 is a second side elevation view of the table tennis paddle of FIG. 1.

FIG. 6 is a top end elevation view of the table tennis paddle of FIG. 1; and,

FIG. 7 is a bottom end elevation view of the table tennis paddle of FIG. 1.

The broken lines shown are for illustrative purposes only and form no part of the claimed design.

1 Claim, 7 Drawing Sheets
